ATTORNEY

UNITED STATES PATENT OFFICE.

THOMAS BENFIELD, OF NEWARK, NEW JERSEY.

DESIGN FOR A WATCH-CASE.

SPECIFICATION forming part of Design No. 19,589, dated January 21, 1890.

Application filed November 5, 1889. Serial No. 329,368. Term of patent 14 years.

To all whom it may concern:

Be it known that I, THOMAS BENFIELD, a subject of Her Majesty the Queen of Great Britain, and a resident of Newark, in the county of Essex and State of New Jersey, have invented and produced a new and original Design for Watch-Cases, of which the following is a specification, reference being had to the accompanying drawing, forming part thereof.

My design consists in a lid or cover of a watch-case having upon its surface a series of stripes or bands of different colors or shades of color.

The leading feature of my design, therefore, may be considered as comprising a circular field in which are a greater or less number of narrow bands of different colors or shades of color and parallel with each other, as shown in the drawing forming a part of this specification.

Referring to the drawing, A represents a figure showing any conventional and well-known design. This figure or representation, however, is no part of my present invention. ²⁵

B represents a band passing across the field of the cover.

C represents another band contrasting in color or shade with that represented by B, while D represents still another band or stripe contrasting in color or shade of color with those represented by B and C. ³⁰

What I claim is—

The design for a watch-case herein shown and described. ³⁵

Signed at New York, in the county and State of New York, this 22d day of October, 1889.

THOMAS BENFIELD.
